DESIGN FOR A SOAP BOX

Sydney L. Parry, Cleveland, Ohio

Application April 20, 1933. Serial No. 47,843

Term of patent 3½ years

To all whom it may concern:

Be it known that I, SYDNEY L. PARRY, a citizen of the United States, whose post-office address is 1322 E. 142nd Street, Cleveland, Ohio, have invented a new, original, and ornamental Design for a Soap Box, of which the following is a specification, reference being had to the accompanying drawing, forming part thereof.

Fig. 1 is a top plan view of the article showing my new design; and

Fig. 2 is a perspective view.

This design for a box embodies nickel-plated side walls, the top and bottom being of bakelite, the top being decorated with sprays of palm and an olive in green upon the black background of the top.

I claim:

The ornamental design for a soap box, as shown and described.

SYDNEY L. PARRY.
